FIG. 2.

UNITED STATES PATENT OFFICE.

CHARLES R. UHLMANN, OF PEORIA, ILLINOIS.

LOCK.

SPECIFICATION forming part of Letters Patent No. 350,573, dated October 12, 1886.

Application filed July 24, 1886. Serial No. 208,913. (No model.)

To all whom it may concern:

Be it known that I, CHARLES R. UHLMANN, of Peoria, in the county of Peoria, State of Illinois, have invented an Improved Lock; 5 and I do hereby declare that the following is a full, clear, and exact description thereof.

The object of this invention is the construction of improved devices for securing the bolt of a door-lock, and so closing the key-hole as 10 not only to prevent sight therethrough, but keep the key from being turned.

This invention is in fact an improvement over a patent of mine dated August 17, 1886, No. 347,664.

15 In the drawings connected with this application, Figure 1 is an interior view of a part of a rim-lock, showing the bolt protracted and secured by my device. Fig. 2 is a section at $\alpha\alpha$ in Fig. 1. Fig. 3 exhibits a modified arrangement of the device; Fig. 4, view of slot through lower rim of the lock-case; Fig. 5, modified form of said slot.

The lock-case L, having its front plate removed, shows the bolt D and the key M. My 25 device for closing the key-hole and holding the key M consists of the securing-block A, adapted to be moved upon the lower rim, L', of the lock-case L by means of the button E, whose stem E' projects below said securing-block through a slot in said rim. One end of the securing-block A is formed with the sloping face C and with the depression C', said sloping face being designed to support the web of the key, while said depression makes room 30 for the stem of the key, so that said end of the securing-block can be moved entirely across the key-hole. Thus not only is the key M prevented from being turned toward the securing-block, but the key-hole is so tightly 35 closed as to keep any one from seeing through the same. By providing the bolt D with a shoulder, D', adapted to engage with a portion of the securing-block, as in Fig. 3, said bolt, as well as the key, cannot be unlocked.

40 In Fig. 1 I show the securing-block A placed in the lock-case L at the side of the key-hole opposite to the position thereof previously described. In this case it is not necessary to have the said block and the bolt provided with 45 means of engagement, since the key is prevented by the securing-block from approaching the bolt to unlock it. The securing-block,

in addition to keeping the key from being turned, so completely covers the key-hole as to prevent the insertion therein of any wire or 55 tool by which to reach and disturb the lock.

In the arrangement of the securing-block shown in Fig. 3, the shoulder D' of the bolt and the shoulder B of the securing-block serve by their engagement, when the bolt is locked 60 and the said block fastened, to prevent the bolt from being retracted. The securing-block does not, however, keep the key from coming in contact with the bolt. It simply does not permit the bolt to be moved, while the improved construction of Fig. 1 keeps the key 65 from the bolt.

To fasten the block A in either its securing position or that of disengagement, I provide the stem E' of the button E with the shoulder 70 E'', adapted to be moved through the enlarged terminal portions of the slot F in the rim L' of the lock-case, but too large to pass the contracted central portion or neck F'.

In Fig. 2 the button E is shown elevated 75 sufficiently to bring the shoulder E'' above the rim L' of the case. When thus elevated, the portion of the stem E' below said shoulder, being made slender enough, can easily enter the neck of the slot F, and, therefore, there is 80 nothing to prevent the securing-block from being moved back and forth upon the rim L'. As soon, however, as the button E is lowered the shoulder E'' enters the slot F at either enlarged end, and, being unable to pass 85 the neck F', locks the block A in either of the desired positions.

The stem E' of the button can be adapted to be vertically movable in recesses in the arm A' of the securing-block and to be depressed by 90 gravity, as in said prior application of my own. I prefer, however, to aid the lowering of the button E by means of a spring, and to locate the stem E' in the body of the securing-block. This I do by forming the vertical 95 transverse slot A² in said block and the vertical passage A³ through the under side of the block into said slot, said passage being fitted to admit the shouldered portion of the stem E'. The upper part of the stem E' is 100 formed into the slender pin E'', whose end enters a vertical pin-hole through the upper wall of the slot A². A spiral spring, S, being mounted on said pin E'', and abutting against

the shoulder E^2 of the stem and the upper wall of the slot A^2 , is thereby adapted to impress the button in the desired downward direction. A small cross-pin, E' , inserted transversely 5 through the upper part of the shoulder E^2 , prevents, by its engagement with the under wall of the slot A^2 , the stem of the button from dropping out of place.

In using my lock, the key being inserted and 10 the bolt shot thereby into engagement with the door-jamb, all that is necessary to do is simply to press up on the button E , and while thus pressing move it sidewise toward the key. When the button cannot be moved further, the button is released and, locking itself, 15 the securing-block A is found to be immovable and the key firmly fastened. From the under side of the securing-block A projects the rib A^5 , fitting loosely in the slot F , the object of 20 the same being to steady the movement of the block. Laterally from the said rib project the shoulders A^4 , secured thereto by pins or in any suitable way, and designed for keeping the block A from rising from the rim. I often, 25 however, omit said shoulder and the rib.

By cutting away the button E and the lower part of the stem E' , and prolonging the cross-pin E' out through a suitable slot made in the side, or, rather, the front of the lock-case, my 30 securing-block A is readily adapted for application to mortise-locks, as well as to rim-locks, for which latter form I have shown the same in the drawings to be adapted, and described it in the papers. A corresponding slot in the 35 incasing-wood is of course necessary in addition to that in the case.

What I claim as my invention, and for which I desire Letters Patent, is as follows, to wit:

1. In a lock, the combination, with the case 40 and the bolt, of the securing-block A , having the face C and the depression C' , and means for securing said block, whereby the lock-key

can be firmly held and the key-hole tightly closed, for the purpose set forth.

2. In a lock, the combination, with the lock-case and the bolt, of the securing-block movable upon the lower rim of the case and having the slot A^2 therein, the button E , having its stem extend up into said slot, and provided with projections engaging, when depressed, 45 with portions of the case, and the spiral spring S , mounted on the upper part of said stem and abutting against the upper wall of said slot, for the purpose specified.

3. In a lock, the combination, with the lock-case having the centrally-contracted slot F in the lower rim thereof, of the bolt, the securing-block movable upon said rim and the stem vertically movable in said securing-block and having the shoulders E^2 , adapted to engage the 50 slot, substantially as and for the purpose set forth.

4. In a lock, the combination, with the lock-case and the bolt, the lower rim of the case having the centrally-contracted slot F , of the 55 securing-block A , having the sloping face C and depression C' , and the vertical transverse slot A^2 of the button E , having the stem E' , provided with the shoulder E^2 , said stem extending through said slot F up into said slot 60 A^2 , the cross-pin E' , for preventing the withdrawal of said stem, and the spiral spring S , mounted upon the upper portion of said stem and abutting against the upper wall of the slot A^2 , substantially as and for the purpose 65 set forth.

In testimony that I claim the foregoing invention I have hereunto set my hand this 13th day of July, in the year 1886.

CHARLES R. UHLMANN.
